Specification for Design.

Patented Nov. 30, 1920.

Application filed April 23, 1920. Serial No. 376,146. Term of patent 14 years.

To all whom it may concern:

Be it known that I, CHARLES BAUM, a citizen of the United States, and resident of the borough of Brooklyn, in the city and State of New York, have invented a new, original, and ornamental Design for a Snap-Fastener, of which the following is a specification, reference being had to the accompanying drawing, forming part thereof.

My new design for a snap fastener is shown in the accompanying drawing, in which—

Figure 1 represents a front view of a snap fastener.

Fig. 2 represents a back view of the same, and

Fig. 3 represents a side view.

I claim:

The ornamental design for a snap fastener substantially as shown.

CHARLES BAUM.
